SEWER CONSTRUCTION

George F. Egan, Jersey City, N. J.

Application September 9, 1940, Serial No. 355,946

4 Claims. (Cl. 182—26)

The present invention relates to sewer construction.

A sewer system ordinarily comprises piping, commonly called a main sewer, constructed or laid beneath the surface of a highway, and such highway generally includes a vehicular roadway, sidewalks along which foot passengers may travel, curbs between the vehicular roadway and the sidewalks, and gutters along the curbs. Ordinarily the surface of a vehicular roadway is 10 fashioned with a crown at or near its center, and from the crown the surface of the vehicular roadway slopes towards the gutters. Sidewalks are ordinarily constructed or laid with a pitch towards the gutters. Rain water and other materials from sidewalks and from the surface of vehicular roadways may be swept or otherwise discharged into gutters and the discharge into gutters may include paper, tree leaves, branches of trees, sticks, tin cans, bottles, decayed fruits and vegetables, animal manure and other materials.

In proximity to gutters are catch basins so located and constructed as to be adapted to receive contents of gutters. Liquids and other materials from roadways and sidewalks may enter catch basins directly instead of being first discharged into a gutter. A catch basin generally has a removable cover. While access to a catch basin may be obtained to clean or repair a catch basin by removing the cover thereof it not infrequently happens that the cover of the catch basin is removed without authorization and the catch basin used as a place for the deposit of dead dogs, rodents, decayed fruits and vegetables, and other materials. Conduits lead from catch basins to the main sewer.

Conduits also lead to the main sewer from buildings on either side of the main sewer. These last mentioned conduits are intended for the discharge into the main sewer of liquids, excrement and other materials from toilets, wash basins, wash tubs, sinks, bath tubs, and other equipment of buildings intended to be served by the main sewer. Toilets, wash basins, wash tubs, sinks, bath tubs, and other paraphernalia, may be installed in more than one part of a building, and the waste piping of the building may be so arranged that waste from toilets, wash basins, wash tubs, sinks, bath tubs, and other paraphernalia from more than one part of the building may discharge into a conduit leading from the building to the main sewer, or the waste piping may be so arranged as to serve as a conduit leading to the sewer. In either event, if discharge from

5 toilets, wash basins, wash tubs, sinks, bath tubs, or other equipment of the building to the main sewer be interfered with waste from toilets, wash basins, wash tubs, sinks, bath tubs, or other paraphernalia in one part of the building may 10 discharge into toilets, wash basins, wash tubs, sinks, bath tubs, or other paraphernalia in another part of the building and out onto the floor of the building.

A conduit leading from a catch basin may become choked if materials from such catch basin cannot pass through such conduit into the sewer, and a conduit leading from a building may become choked if materials from the building 15 cannot pass through the last mentioned conduit into the sewer. Obviously whatever liquids and materials may be in a catch basin when the conduit leading from the catch basin to the sewer is choked, may not discharge into the sewer and entrance of liquids and other materials into a catch basin from gutters, etc., while the conduit leading from the catch basin to the sewer is choked may result in the flooding of the highway. If the exit of waste from toilets, wash 20 basins, wash tubs, sinks, bath tubs, or other paraphernalia, to the sewer be choked, such waste may seek exit wherever it can find an opening in the building and this may result in the flooding of the cellar or basement of the building, 25 and in the discharge of waste onto the flooring of the building.

30 Sewage entering a main sewer includes excrement and other materials from buildings and leaves, dirt, and other materials from catch basins. Excrement, for instance, adheres to the bottom and sides of the sewer and becomes hardened and materials from buildings and catch basins may adhere to the bottom and sides of the sewer or to excrement or other materials with which the interior of a sewer is coated, and adherence of materials to the bottom and sides of a sewer or to materials with which the interior of a sewer is coated reduces the diameter of a sewer. If sewage entering a sewer cannot flow towards the body of water into which it is intended that sewage shall be discharged and be there discharged into such body of water the sewer itself may be choked and the conduits leading to the sewer from catch basins and buildings may be unable to freely discharge into the sewer. And if contents of the body of water into which it is intended that sewage shall be discharged enter the sewer not only may the flow of sewage towards the discharge end of the sewer and the discharge of sewage from such discharge

end be interfered with but contents of the sewer and of the body of water into which it is intended that sewage may discharge may ascend into the conduits intended to empty into the sewer and out into catch basins and buildings with which such conduits are connected. The results of the flow into a sewer of water from the body of water into which it is intended that sewage shall discharge do not appear to require further elaboration.

Ordinarily, a main sewer is constructed or laid with an inclination towards a body of water into which body of water liquids and materials carried by liquids to the discharge end of a sewer, may empty. Ideally, the discharge end of a sewer should be above the high water line of such body of water but it frequently happens that a locality intended to be served by a main sewer is so low that it is impracticable to so locate the discharge end of a main sewer that said discharge end shall at all times be above the high water line of the body of water into which it is intended that the main sewer shall empty. When the water into which it is intended that a sewer shall discharge rises sufficiently not only is the discharge of liquids and materials carried by liquids from the main sewer into such body of water interfered with, but the body of water may enter the discharge end of the sewer and into conduits leading to the sewer from buildings and catch basins intended to be served by the sewer.

An object of the present invention is to provide a sewer construction comprising means whereby a sewer will at all times be free to discharge contents thereof into the body of water into which it is intended that the sewer shall empty and at the same time prevent such body of water from entering the sewer.

Another object of the invention is to provide a sewer construction wherein movement towards the discharge end of a sewer of liquids and materials carried by liquids will be accelerated.

The invention also contemplates provision of a valve located below the high water line of a body of water into which it is intended that movable contents of a sewer may discharge, which valve will automatically prevent flow into a sewer of contents of the body of water into which it is intended that the sewer shall empty.

With foregoing and other objects in view the present invention will be more fully described hereinafter and will be more particularly pointed out in the claims appended hereto.

In the drawings, wherein like symbols refer to like or corresponding parts throughout the several views:

Fig. 1 shows parts of a main sewer embodying my invention in side elevation and with the discharge end of a lower branch submerged in a body of water.

Fig. 2 is a fragmentary view of a discharge end of a lower branch part in the act of discharging into a body of water.

Fig. 3 is a front view of a portion of a sewer embodying my invention and showing two branches at the discharge end of the sewer.

Fig. 4 is a perspective view of one form of valve.

Fig. 5 is a fragmentary perspective view of the discharge end of a lower branch shown in Fig. 1.

Fig. 6 is a side view, with parts broken away, showing another form of a discharge end of a sewer.

Fig. 7 is a partial side and sectional view of a lower branch showing a modified form of valve construction and band.

Fig. 8 is an end view of the construction illustrated in Fig. 7.

Fig. 9 is a cross section taken on the line 9—9 of Fig. 7;

Fig. 10 is a front view of a modified form of valve; Fig. 10a is a cross section of the form of valve illustrated in Fig. 10; Fig. 11 is a front view of another modified form of valve; and Fig. 11a is a cross section of the form of valve shown in Fig. 11.

Referring to the drawings and for the present more particularly to Figures 1 to 5, inclusive, 60 designates part of a sewer the discharge end whereof being shown as provided with a lower branch 61 and an upper branch 62. The branch 61 is shown as having an inclination downwardly towards the body of water indicated to the left in Fig. 1 greater than the inclination of the piping 60 towards said body of water. When the pressure of the contents of the branch 61 against the valve hereinafter referred to is greater than the weight of the valve and such pressure as is exerted to hold said valve closed contents of the branch 61 may be discharged into the body of water into which it is intended that sewage may be discharged. In Fig. 1 said body of water is shown at high water line and the valve at the discharge end of the branch 61 is shown as completely immersed in said body of water, while the discharge end 64 of the upper branch 62 is shown as terminating above the high water line of said body of water and as discharging downwardly and forwardly beyond the valve at the discharge end of the branch 61. The branch 62 is shown as joined to the pipe 60 at 65, located back of the point 63 where the more precipitate inclination of the branch 61 is shown as beginning, and the connection at 65 is shown as made at the upper side of the pipe 60 and as covering an area relatively greater than the diameter of the branch 62.

The discharge end of branch 61 is shown as extending beyond the bank 66 of the body of water into which it is intended that sewage shall be discharged, and this projecting end of the branch 61 is shown as provided with a circumferentially elongated slot 68 located near the discharge end of the branch 61. The discharge end of the branch 61 is shown as so arranged and disposed that the upper portion thereof will lie inwardly of the lower portion and permit the valve to rest against the discharge end of the branch 61. In Fig. 4 the valve 67 is shown as provided with a tongue made integral with the valve 67 and a portion 70 of the tongue 69 is shown as extending radially outward from the valve 67 to permit the valve to rest against the discharge end of the branch 61. The tongue 69 is shown as turned over from the upper edge of the part 70 and so bent as to lie around the outer circumference of the branch 61 between the discharge end of the branch 61 and the slot 68. This portion of the tongue 69 is indicated at 71. The portion 72 of the tongue 69 is shown as bent downwardly and as entering through the elongated slot 68, and the tail piece of the tongue is shown as curved downwardly and rearwardly from the lower edge of the part 72. A hinged joint is formed whereby the valve 67 may rock at the discharge end of the branch 61, and the tail piece 69 will prevent the valve from disengaging itself from the branch 61.

In Figures 1, 2 and 3 I have shown a valve concavo-convex in shape with the convexity presented to the discharge end of the branch 61. In Fig. 1 I have shown the valve as fitting snugly in the discharge end of the branch 61. When the valve is in the position shown in Fig. 1 the weight of the valve will aid in holding the valve closed and the convexity of the valve will aid the body of water into which it is intended that sewage shall be discharged in holding the valve closed.

The operation of the form of invention shown in Figures 1, 2 and 3 is as follows: The discharge end of the branch 61 will preferably be disposed at as high a point as practicable above the low water mark of the body of water into which it is intended that sewage may discharge and the discharge end 64 of the branch 62 will be so disposed and arranged that the end 64 will be at all times above the high water line of such body of water. When pressure of sewage in the branch 61 against the valve 67 is greater than the pressure of the weight of that valve against the discharge end of the branch 61, sewage may empty from the discharge end of the branch 61 provided the body of water into which it is intended that sewage shall discharge does not press against the valve 67. When said body of water presses against the valve 67, the valve 67 will be held closed and there will be no counter or back flow from said body of water into the sewer. On the other hand sewage may freely discharge through the branch 62.

The arrangement illustrated in Fig. 6 is substantially similar to the arrangement shown in Figures 1 to 5 inclusive. In Fig. 6, 74 designates part of a sewer, 75 a lower branch, 76 an upper branch, and 77 the place at which the precipitate inclination of the branch 75 commences. In this form of construction, the branch 76 is shown as connected at 78 with the branch 75 outwardly of the point 77. In Fig. 6 the valve at the discharge end of the branch 75 is of the form illustrated in Fig. 11. The branches 75 and 76 may be made together. The general construction, functions and operations of device shown in Fig. 6 are substantially the same as those of the construction illustrated in Figures 1 to 5, inclusive.

In Figures 7, 8 and 9, the branch 61 is shown as provided with a band 79 secured at the discharge end of the branch 61 as by fastenings 80 and as having a flange 81 bent over the discharge end of the branch 61 for receiving the edge portion of the valve 67. The band 79 is shown as provided with an inturned lip 82 at its upper portion bent through a slot 68. The band 79, its flange 81 and lip 82 provide wear surfaces for the valve 67 to rock on. Furthermore, the band 79 reinforces and strengthens the discharge end of the branch 61. This form of construction is applicable for use where the branch 61 is of a material other than metal. The band 79 may be removed and replaced whenever desired.

In Fig. 10 there is shown a valve 142 of concavo-convex cross-section and with double hanging eyes 143 and 144 and in Fig. 11 there is shown a concavo-convex valve with a single eye 148.

All these forms of valve operate to open and close the discharge end of the branch 61 in the

same manner as is described in connection with Figures 1 to 6 inclusive.

It is obvious that various changes and modifications may be made in the details of construction and design of the above specifically described embodiments of my invention without departing from the spirit thereof.

I claim:

1. A sewer construction comprising sewer piping extending at an inclination towards a body of water, an end portion terminating below the high water line of said body of water, a valve mounted at the terminal of said end portion, said valve being of such weight and of such shape and so mounted that it will close said terminal except when contents of the sewer force said valve open, and the terminal of said end portion being of such shape that the valve will rest thereagainst and close said end portion except when said valve is held open by pressure from within said sewer, and another end portion having a terminal located above the high water line of said body of water.

2. A sewer construction comprising sewer piping extending at an inclination towards a body of water, an end portion terminating below the high water line of said body of water, a concavo-convex valve mounted at the terminal of said end portion and adapted to hold said terminal of said end portion closed except when pressure from within the sewer holds said valve open, the convex portion of the valve being adapted to fit into the terminal of said discharge end and the terminal of said discharge end being adapted to receive the convex portion of the valve therein, and another end portion having a terminal located above the high water line of said body of water.

3. A sewer construction comprising sewer piping extending at an inclination to a body of water, an end portion having a greater inclination downwardly towards said body of water than the inclination of the main body of a sewer piping towards said body of water, said end portion having a valve mounted at the terminal thereof, said valve being of such weight and of such shape and so mounted that it will close said terminal except when contents of the sewer holds said valve open, and the terminal of said end portion being of such shape that the valve will rest thereagainst except when said valve is held open by pressure from within said sewer, and another end portion having a terminal located above the high water line of said body of water.

4. A sewer construction comprising sewer piping extending at an inclination towards a body of water, an end portion terminating below the high water line of said body of water, a valve mounted at the terminal of said end portion and adapted to rest against said terminal except when contents of the sewer holds said valve open, said valve having a tongue integral therewith and said end portion having a perforation in the circumference thereof adapted to receive said tongue, the end of said tongue which enters said perforation being so turned within said end portion that said valve is adapted to rock on said end portion, and another end portion having a terminal located above the high water line of said body of water.

GEORGE F. EGAN.
